UNITED STATES PATENT OFFICE.

VICTOR VIVAUDOU, OF NEW YORK, N. Y.

CONTAINER.

Application filed October 16, 1922. Serial No. 594,871.

To all whom it may concern:

Be it known that I, VICTOR VIVAUDOU, a citizen of the United States, residing at New York city, county of New York, borough of Manhattan, and State of New York, have invented new and useful Improvements in Containers, of which the following is a full, clear, and exact specification.

My invention refers to containers and refers particularly to containers suitable for employment with powder masses.

One of the objects of my invention is a container suitable for the retention of masses or compacts, of face powder and similar products.

In the employment of powder compacts of the character mentioned, the powder is pressed into a solid mass, or compact, which is then attached by means of an adhesive to a supporting plate, usually of metal, in order to prevent, as far as possible, the breaking and disintegration of the mass during its use.

The compact thus affixed to the supporting plate is then fixedly attached to the inside face of a container, in order to protect it during non-use.

This contact between the supporting plate and the face of the container is usually accomplished by means of an adhesive, but as the two abutting surfaces are of metal, considerable difficulty is experienced in producing a sufficiently permanent jointure to withstand the use to which the device is applied.

In addition to the above-mentioned difficulty, a device of this character possesses the further disadvantage that, when the compact is consumed, or broken, it is necessary to purchase a new container, as it is practically impossible for the ordinary user to affix a new compact therein.

The device of my invention overcomes all of these, and other, difficulties and disadvantages and presents a new and useful device possessing advantages not incident to the former devices, as described above.

My invention comprises a device in which the supporting plate, carrying the compact, is capable of mechanical attachment to an inner face of the container, preferably by thread engagement, thus insuring a firm attachment while allowing of the easy removal of an old compact and attachment of a new compact.

The novelty and advantages of my de-

vice will be evident upon a consideration of my specification and accompanying drawings.

In the accompanying drawings, illustrating modified forms of the device of my invention, similar parts are designated by similar numerals.

Figure 1 is a perspective view of one form of my device in closed position. 65

Figure 2 is a top plan view of Figure 1 in open position.

Figure 3 is a cross-section through the line 3—3 of Figure 1.

Figure 4 is an enlarged vertical cross-section of the attaching means of Figure 3. 70

Figure 5 is a vertical cross-section of a modified attaching means.

Figure 6 is a vertical cross-section of a modified attaching means. 75

Figure 7 is a vertical cross-section of a modified attaching means.

The particular form of the device of my invention, shown in the accompanying drawings, comprises a container having the bottom 10, the upwardly extended side flange 11 and the top 12 hinged to the flange 11 at 13. 80

Situated within the container is a powder compact 14 fixedly attached to the supporting plate 15 by means of glue or otherwise. 85

The supporting plate 15 has a fixedly attached centrally positioned member 16 extending below its bottom face, the extended portion carrying a thread capable of meshing with the thread within the centrally positioned opening 17 of the bottom 10. 90

In the modification shown in Figure 5, the bottom member 10 has a fixedly attached annular extended member 18 having a centrally positioned threaded opening 19. The supporting plate 15 has a centrally positioned annular recess 20, the extended threaded portion of the member 16 meshing with the threads in the opening 19. 100

In the modifications shown in Figures 1 to 5 inclusive, the extended threaded member 16 is fixedly attached to the compact-supporting plate 15 and is capable of being threaded into an opening within the bottom 10 or an opening within a member carried thereby. 105

In the modifications shown in Figures 6 and 7, the extended threaded member is carried by the bottom 10 and threads with an opening in the compact-supporting plate 15. 110

In the device of Figure 6, the bottom 10

has a riveted upwardly extended threaded member 21 capable of meshment within the threaded opening 22 of the compact-supporting plate 15.

5 In the device of Figure 7, an upwardly extended threaded member 23 is soldered, or otherwise fixedly attached, within the recess 24 of the bottom 10 and is capable of meshment within the threaded opening 25 of the 10 compact supporting plate 15.

A mirror 26 is carried by the interior of the top, or cover, 12 and a powder puff 27 may be carried within the device.

From the above description of my invention, it is evident that a firm attachment is made between the container and the supporting plate and that the compact and supporting plate may be readily removed and replaced.

15 20 I do not limit myself to the particular

size, shape, number, arrangement or material of parts, as shown and described, all of which are given simply as a means for clearly explaining my invention.

What I claim is:—

25 A container comprising a top member, a bottom member having rigidly attached thereto a threaded member, a compact-supporting member having rigidly attached thereto a threaded member capable of meshment with the threaded member of the bottom member upon rotation of the compact-supporting member with respect to the bottom member and a frangible, solid powder compact fixedly attached to the compact-supporting member.

30 35 Signed at New York city, in the county of New York and State of New York this 11th day of October, 1922.

VICTOR VIVAUDOU.
